United States Patent Office.

L. H. BECKWITH, OF PORT JERVIS, NEW YORK, ASSIGNOR TO HIMSELF, M. COLGAN, OF SAME PLACE, AND M. M. LIVINGSTON, OF NEW YORK CITY.

Letters Patent No. 68,840, dated September 3, 1867; antedated August 19, 1867.

IMPROVED BENDING MACHINE.

The Schedule referred to in these Letters Patent and making part of the same.

TO ALL WHOM IT MAY CONCERN:

Be it known that I, L. H. BECKWITH, of Port Jervis, in the county of Orange, and State of New York, have invented a new and useful Machine for Bending Couplings and Pins for railroad cars, links, hooks, etc., etc.; and I do hereby declare that the following is a full, clear, and exact description of the same, reference being had to the accompanying drawing, making part of this specification.

My invention consists in the combination of a suitable holding-box, former, and forming lever, so arranged that the proper shape may be given to the rod or bar of metal to be bent. It consists also in the combination with such holding-box of a cam-clamp, or its equivalent, for clamping or holding the rod or bar of metal in the holding-box whilst being bent. It also consists in the combination with such holding-box of an adjustable set-screw for regulating the distance the rod or bar is to be thrust into the holding-box, so that a coupling, when bent, will have both its legs or sides of an equal length, and ready for being welded together. In the accompanying drawings—

Figure 1 is a side elevation of my invention, partly in section.

Figure 2 is a plan or top view of the same.

The machine I have illustrated is intended for bending railroad-car couplings at one of its ends, and coupling-pins at the other. Each feature has, however, a similar mode of operation. I shall describe first that part of my invention designed for making couplings, links, etc.

A designates the former, or that part of the machine over which the metal is bent to give it the required form or shape. B is the holding-box, and it is arranged in such relation to the former that it will hold one leg or half of the rod or bar whilst the other is being bent or formed. In the present instance this holding-box is made in the stock or body of the machine below the part called the "former" A, and the metal which is to be formed into the link, coupling, or other article, after being forced for the proper distance into the holding-box, is held immovable therein by a cam-shaped clamp, C. D is a set-screw, carrying on its end a stop-piece, s, arranged to travel in the holding-box B. This set-screw can be moved back and forth in a slot made horizontally in the stock or body of the machine. By moving this stop s to the desired point in the holding-box, and screwing up the set-screw D, the distance the rod or bar is to be thrust into the holding-box can be regulated, and hence the said rod or bar may be bent so that both its legs will be of exactly the same length. The forming device consists of a lever, E, provided with one or more rollers a a. The lower end of this lever is bifurcated, and the rollers (there are two shown in the drawing) are axled between the two legs, and the two legs are bent near their ends at right angles to the rest of the lever, as shown at b, and pivoted at their ends to the former A. The rollers are thus brought down below the mouth of the holding-box B, so as not to interfere with the insertion therein of the rod or bar, and at the same time in a proper position to operate on the said rod or bar for bending it over the former.

In operating the machine for bending couplings for railroad cars the forming-lever is thrown down in a horizontal position; the set-screw is adjusted so that the stop-piece will regulate the length of the leg within the holding-box. The cam-shaped clamp is then brought to bear on the rod or bar to hold it. The forming-lever is then forced upward, and the rod or bar is then bent over the former. The horse-shoe shaped coupling may then be removed, and the ends welded together in the usual way over the horn of the anvil.

I will here remark that in bending couplings, as now practised, the most difficult and tedious part is to bend the rod or bar so that the two legs will be of the same length. To explain: the practice commonly employed in railroad repair shops is to bend the bar or rod gradually and carefully in a fork-shaped device, called a "former," which is placed in the "hardy-hole" of the anvil. By degrees the rod is bent, but it is very seldom that the two legs are of the same length; hence it is necessary to crowd down the longer leg till both legs are of the same length, when they can be bent towards each other and welded together over the horn of the anvil.

I will now describe that part of my invention designed for bending coupling-pins.

F is the holding-box, which is made in the upper part of the former. The end of the machine in this instance constitutes the former, and it is lettered G on the drawings. H is the forming-lever. This is bifur-

cated, and its legs *c c* straddle the former, and are pivoted thereto. A roller, *g*, which is grooved to correspond to the rotundity of the pin, is axled between the said legs *c c*. A set-screw, *I*, carrying a stop-piece, *f*, and arranged to operate similarly to that, *D*, is employed, and its office is to regulate the length of the pin before its end is turned down to form the head.

The operation of this part of the machine is obvious. A coupling-pin of simple construction, and one that can be quickly made, is produced by this machine.

It is evident that the forming-levers can be arranged in different ways, and secured otherwise than directly to the formers, and yet bear the same relation to the said formers and holding-boxes as herein described; and it is also evident that the holding-boxes may be separate from the formers. It is also evident that the rollers may be grooved in any way, according to the shape of the bar or rod to be bent; and that the holding-boxes and formers may be of a corresponding character; and the rollers may be stationary, if desired, or the lever may be solid instead of being provided with rollers, and the bending be effected.

What I claim as my invention, and desire to secure by Letters Patent, is—

1. A forming-lever, in combination with a holding-box and former, the whole constructed and arranged substantially as described, and having a mode of operation substantially as set forth.
2. The combination of the set-screws *D* and *I* and stops *F*'s with the holding-boxes, substantially as and for the purpose herein specified.
3. The cam-shaped clamp *C*, in combination with the holding-box *B* and adjustable stop *s*, substantially as specified, for holding the bar or rod in the holding-box whilst being operated upon.

L. H. BECKWITH.
